Primary Examiner — Clint A Samuel*(74) Attorney, Agent, or Firm* — Jose Cherson Weissbrot(57) **CLAIM**

The ornamental design for a sleep aid light, as shown and described.

DESCRIPTION

FIG. 1 is a first perspective view of a sleep aid light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the sleep aid light thereof;

FIG. 10 is an exploded view of the sleep aid light thereof; and,

FIG. 11 is an enlarged view of the selected portion 11 in FIG. 1.

The broken lines shown in the drawings depict portions of the sleep aid light that form no part of the claimed design.

1 Claim, 11 Drawing Sheets(56)
